UNITED STATES PATENT OFFICE.

CHESTER MOTT, OF DENVER, COLORADO, ASSIGNEE, BY MESNE ASSIGNMENTS, TO
PUROX COMPANY, OF DENVER, COLORADO, A CORPORATION OF COLORADO.

DETONATOR FOR LIQUID-OXYGEN EXPLOSIVES.

Application filed April 29, 1924. Serial No. 709,781.

To all whom it may concern:

Be it known that I, CHESTER MOTT, a citizen of the United States, residing in the city and county of Denver, State of Colorado, have invented a new and useful Detonator for Liquid-Oxygen Explosives, of which the following is a specification.

My invention relates to the art of blasting and is particularly applicable to blasting with the use of liquid oxygen. In this art, a cartridge is prepared from absorbent carbonaceous material, this cartridge being soaked in liquid oxygen and exploded by a suitable detonator. I have found that the

ordinary detonators are not suitable for this purpose and it is a particular object of my invention to provide a detonator that can be depended upon under all conditions of use.

The present mercury fulminate detonator or other familiar detonators or blasting caps are merely cylindrical shells closed at one end; the other end being left open to receive the fuse which is crimped into the detonator or blasting cap. With liquid oxygen cartridges it is not practicable to insert the blasting cap and fuse into the cartridge in such a way as to anchor it. With dynamite cartridges the fuse and cap are laced in in such a way that when the cartridges are rammed home certain anchorage is secured for the fuse in the hole. It does not suffice to lay a cap and fuse alongside liquid oxygen explosive cartridges for the explosion of previous shots is almost certain to pull the fuse and its cap from the hole. It is, therefore, an object of my invention to provide a certain anchorage of the cap and fuse in the hole to insure its not being pulled out.

Further objects and advantages will be made evident hereinafter.

Referring to the drawing which is for illustrative purposes only,

Fig. 1 is a section through a hole prepared for blasting with my detonator.

Fig. 2 is an end view.

Fig. 3 is a side view of the detonator as placed in the hole.

Fig. 4 is a section on an enlarged scale of the detonator before it is bent into shape.

Fig. 5 is a section on a more enlarged scale on the line 5—5 of Fig. 4.

In blasting with liquid oxygen explosive, a bore hole 11 is prepared in which liquid

oxygen cartridges are placed. These cartridges are exploded by a fuse 13 and a detonator 14. The ordinary forms of detonator are not satisfactory when used for this purpose and the special form illustrated has been invented by me. It consists of a body 60 of absorbent carbonaceous material 20 such as charcoal, peat, prepared sawdust, or the like. This material 20 is carried inside a wire gauze tube 21. Situated at one end of the absorbent material 20 is a small amount 65 of acetylidy of copper 22. This acetylidy of copper may be prepared in the following manner.

A saturated solution of cuprous chloride and water is prepared. This solution is 70 made slightly ammoniacal and a little ferrous sulphate is added to keep the solution reduced. Acetylene is then bubbled through the solution and a dark red flocculent precipitate is formed. This precipitate is separated by filtration and partially dried. It is believed that the formula for the substance produced is $Cu_2C_2:H_2O$. I have found that this acetylidy of copper is a 75 very valuable detonator when used in this connection. Adjacent to the acetylidy of copper is the end of an ordinary fuse 23 which is secured projecting into the tube 21 by means of a cover 24 which is braided or wrapped about the entire detonator. The completed detonator is then bent into circular form, as shown in Figs. 2 and 3, having a diameter slightly less than the bore hole and is either placed in the bottom of this hole or between two cartridges in the hole. The end 30 of the fuse 23 is then ignited. The fuse detonates the acetylidy of copper 22, which in turn detonates the absorbing material 21 which has been soaked in liquid oxygen before being placed in the hole. 80

As already stated, the present blasting cap or detonator is not suitable for this purpose, but with the detonator of the shape as shown in the drawing, for the fuse to be withdrawn from the hole it is necessary to pull out the stemming and all of the cartridges on top of the detonator, or to bend the detonator tube out straight. 85

I claim as my invention:

1. A detonator for liquid oxygen explosive comprising: absorbent material; a body of a detonating acetylidy adjacent to said absorbent material; a fuse having one end adjacent 90

- to said detonating acetylid; and means for holding said material, said acetylid and said fuse in their proper relationship.
2. A detonator for liquid oxygen explosive comprising: absorbent carbonaceous material; a body of copper acetylid adjacent to said carbonaceous material; a fuse having one end adjacent to said copper acetylid; a container in which said carbonaceous material and said acetylid are placed; and means for securing said fuse in said container.
3. A detonator for liquid oxygen explosive comprising: absorbent material; a body of detonating material adjacent to said absorbent material; a fuse having one end adjacent to said detonating material; a container formed of fine mesh screen in which said materials are placed; and means for securing said fuse in said container.
4. A detonator for liquid oxygen explosive comprising: absorbent carbonaceous material; a body of detonating material adjacent to said carbonaceous material; a fuse having one end adjacent to said detonating material; a container formed of fine mesh metallic wire screen in which said materials are placed; and means for securing said fuse in said container.
5. A detonator for liquid oxygen explosive comprising: absorbent carbonaceous material; a body of copper acetylid adjacent to said carbonaceous material; a fuse having one end adjacent to said copper acetylid; a container having fine perforations in the wall thereof in which said carbonaceous material and said copper acetylid are placed; and means for securing said fuse in said container.
6. A detonator comprising: a tubular member bent into the form of a ring.
7. A detonator having a ring-shaped portion; and a second portion at an angle to said ring-shaped portion.
8. A detonator having a ring-shaped por-
- tion; and a portion substantially at right angles to the plane of said ring-shaped portion.
9. A detonator having a ring-shaped portion; a second portion at an angle to said ring-shaped portion; and a fuse in said second portion.
10. A detonator comprising: a tubular member bent into the form of a loop.
11. A detonator having a loop portion; and a second portion extending at an angle to the plane of said loop portion.
12. A detonator having a loop portion; a second portion extending at an angle to the plane of said loop portion; and a fuse in said second portion.
13. A detonator having a loop portion; and a second portion extending substantially at right angles to the plane of said loop portion.
14. A detonator having a loop portion; a second portion extending substantially at right angles to the plane of said loop portion; and a fuse in said second portion.
15. A detonator as claimed in claim 1, said detonator being formed into a loop.
16. A detonator as claimed in claim 1, said detonator having a loop portion and a second portion extending at an angle to the plane of said loop portion.
17. A detonator as claimed in claim 2, said detonator having a loop portion and a second portion extending at an angle to the plane of said loop portion.
18. A detonator as claimed in claim 2, said detonator being formed into a loop.
19. In a liquid oxygen detonator, a detonating acetylid as a detonating agent.
20. In a liquid oxygen detonator, copper acetylid as a detonating agent.
- In testimony whereof, I have hereunto set my hand at Denver, Colorado, this 19th day of April, 1924.

CHESTER MOTT.
